Specification of Letters Patent.

Patented Oct. 15, 1912.

Application filed February 21, 1912. Serial No. 679,106.

To all whom it may concern:

Be it known that I, WILLIAM L. MURPHY, a citizen of the United States, and a resident of the city and county of San Francisco and State of California, have invented certain new and useful Improvements in Hinges, of which the following is a specification.

The invention relates to hinges for joining and pivoting together, two hollow or tubular members.

The object of the invention is to provide a hinge which is not perceptible when the hinged members are alined.

Another object of the invention is to provide a hinge for tubular or hollow members, which operates to allow the hinged parts to move through an angle of ninety degrees to each other.

Another object of the invention is to provide a hinge, which when the two elements are in line, produces a substantially rigid structure.

The invention possesses other advantages, which, with the foregoing will be set forth at length in the following description, where I shall outline in full that form or embodiment of the invention which I have selected for illustration in the accompanying drawings.

The novelty of the invention will be included in the claims succeeding said description. From this it will be apparent that I do not restrict myself to the showing made by said drawings and description as I may adopt many variations within the scope of my invention as expressed in said claims.

The hinge is particularly adapted to be used in folding beds for connecting the legs at the foot of the bed to the bed frame and I have so illustrated it in the drawings, but it is to be understood that it may be used in other constructions for hinging together hollow or tubular members.

Referring to the drawings: Figure 1 is a side elevation of the foot of a folding bed, partly elevated, showing the hinge of my invention, Fig. 2 is an end view of the device as shown in Fig. 1, Fig. 3 is a section through the tubular members taken at the hinge, the two parts being shown folded; or at right angles to each other, Fig. 4 is a similar view showing the parts alined and the hinge closed, Fig. 5 is an external view of the closed hinge taken from the right hand side of Fig. 4.

Since the hinge is particularly adapted to be used on beds, I will describe it in such connection. In folding beds it is desirable that the legs at the foot of the bed shall fold against the bed; when it is in the raised position, so that the bed may occupy as small a space as possible. It is also desirable that the connection between the leg and the bed frame be substantially rigid when the bed is lowered and that the hinge be concealed.

The two hinged members 2-3 may be respectively the foot rail of the bed and the leg, the foot rail being rigidly connected to the side rails 4 of the bed frame and being movable with the bed frame. The upper member 2 is provided with an ear or projection 5 having an elongated slot 6 therein which engages a pin 7 arranged in the lower member 3, said pin 7 being the pivot of the hinge. The lower member 3 is provided with a slot 8 in line with the ear 5 and into which the ear moves as the two members move in alinement. The ear 5 is provided with a shoulder 9 which engages the outer surface of the lower member 3 when the parts are moved to a substantially right angle position and holds the parts in such position. The slot 6 in the ear is of such length that when the pin 7 engages the lower end of the slot and the shoulder 9 engages the outer surface of the member 3, the parts are substantially at right angles to each other. When the parts are alined and the pin engages the upper end of the slot the edges 12-13 of the members are in contact.

The upper member 2 is provided with a tapered projection 11 encircling the upper end of the ear which assists in completely alining the two parts so that they seat properly one upon the other. This projection 14 may be formed integral with the member or it may be formed separately and secured in the end of the member. The preferable construction would probably consist in forming the ear and the projection 14 in one piece and driving them into place. The projection 14 takes its form from the shape of the tubular members, that is, if the members were cylindrical it would be conical, and if the members were rectangular it would be pyramidal. Other than serving to aline the members, the projection also increases the rigidity of the joint. The ear 5 is also formed that when the members are

aligned, that side opposite the shoulder 9 lies close to the surface of the member, preventing the members from moving transversely with respect to each other.

5 I claim:

1. A hinge comprising a hollow member provided at one end with a slot, a second member, an ear projecting from said second member provided with a closed end slot, a 10 tapered projection at the base of said ear arranged to seat in said hollow member and a pin secured in said first member engaging in said closed end slot.

2. A hinge comprising a hollow member 15 provided at one end with a slot, a pin in said member arranged transversely of said slot, a second member, an ear projecting from said member provided with a slot engaging said pin, a tapered projection 20 at the base of said ear adapted to seat in the hollow member and a shoulder on said ear

adapted to lie in the slot in the hollow member when the hinge is closed.

3. A joint for tubular frames, said joint including two abutting tubes, one of which 25 has an open slot upon one end, a flat tongue fixed in the other tube extending into the slotted one and slideable therein, said tongue having a slot, a pin fixed in the first mentioned tube upon which the tongue is movable, and a projection on the second tube arranged at the base of said tongue and adapted to engage in the first tube when the tubes are alined and the joint closed.

In testimony whereof, I have hereunto set 35 my hand at San Francisco, Cal., this 14th day of February 1912.

WILLIAM L. MURPHY.
